H. M. EWING.
LIGHT DISSOLVER.
APPLICATION FILED JUNE 17, 1918.

1,401,329.

Patented Dec. 27, 1921.

UNITED STATES PATENT OFFICE.

HOWARD M. EWING, OF LOS ANGELES, CALIFORNIA, ASSIGNOR TO FAMOUS PLAYERS-LASKY CORPORATION, A CORPORATION OF NEW YORK.

LIGHT-DISSOLVER.

1,401,329.

Specification of Letters Patent. Patented Dec. 27, 1921.

Application filed June 17, 1918. Serial No. 240,386.

To all whom it may concern:

Be it known that I, HOWARD M. EWING, a citizen of the United States, residing at Los Angeles, in the county of Los Angeles, State 5 of California, have invented new and useful Improvements in Light-Dissolvers, of which the following is a specification.

This invention relates to illuminating apparatus, more particularly adapted to motion picture illumination; and it is an object of this invention to provide a device which will cause a perfectly gradual dimming or "dissolving" of the light, and, conversely, cause a perfectly gradual brightening of 10 the light, under accurate and complete control of the operator. It is a further object to provide such a device in simple, inexpensive and easily operated form. The device is here shown in form adapted to illumination of scenes etc. for photographic work.

The fundamentals of my invention will be readily understood from the following detailed description of a preferred and specific 25 embodiment of the invention. In this description and in the accompanying drawings I show and describe a form of device having several preferred features; but it will be understood that the invention is not limited 30 to the specific details herein set forth, these details being described for the purpose of clearly describing the whole invention and not for the purpose of limitation.

In the accompanying drawings Figure 1 35 is a small side elevation of a lamp equipped with my improved device; Fig. 2 is an enlarged front elevation of the same; Fig. 3 is a section taken on line 3—3 of Fig. 2; Fig. 4 is a partial plan of the device, the 40 view being taken as indicated by line 4—4 on Fig. 2; Fig. 5 is an enlarged sectional detail taken as indicated by line 5 on Fig. 4; and Fig. 6 is a small view showing the light dissolving curtain itself.

I show my invention applied to two 45 double arc lamps, each of which is contained within a casing 10. Each of these arc lamps has a double light. In practice, there is a central carbon 11 and two lateral carbons 50 12; so that in each lamp there are two horizontally spaced points of illumination as indicated at 1. These points of illumination are spaced apart horizontally (or, more generally speaking, transversely of the line of 55 movement of the dissolve curtain) and the

two sets of points of illumination are spaced apart vertically, or longitudinally of the movement of the dissolve curtain. Now, although my dissolve curtain operates efficiently when applied even to a single lamp 60 having a single point of illumination, it gives most efficient results when applied to such a lamp arrangement as herein illustrated, with one or more sets of spaced points of illumination. The specific construction of the lamps is of course immaterial to the present invention.

The two lamp casings 10 may be supported in any suitable manner, as upon a supporting standard 15. I provide a removable casing 16, which is in the form of a frame adapted to be removably placed upon the lamp casing 10. This frame casing 16 has a rear frame 17 made to fit around the forward ends of the lamp casings. Extending 70 forwardly of the frame 17 there is a sort of frame boxing, preferably made of sheet metal, and having sides 20 and top and bottom 21, and having at its front an opening which is surrounded by top and 75 bottom flanges 22 and side flanges 23. The dissolve curtain 24 covers the opening, and the edges of the dissolve curtain lie behind these flanges at opposite edges of the opening. At the top and bottom of the frame 80 casing there is a box 25 (see Fig. 3); in which boxes are housed the two rollers 27 upon and between which the curtain 24 is carried. These two rollers are provided with crank handles, or with any other suitable 85 means for causing their rotation, whereby either of the rollers may be rotated to draw the curtain 24 either up or down.

The curtain 24 is made of any suitable material and has one end portion 30 relatively 90 transparent and the other end portion 31 relatively opaque. In actual practice, and in a preferred form of the device, I make this curtain of a suitable fabric, and preferably of thin silk; and the portion 30 is 95 made of white silk, or silk of some light color, so that it is relatively highly transparent or translucent; and the portion 31 I make preferably of black or some dark colored silk, so that this portion 31 is relatively 100 opaque. (It is not necessarily absolutely opaque. It may be only relatively so; or it may be opaque, or relatively opaque, to actinic rays by being suitably colored). The preferred method of joining the two 110

- portions of the curtain is shown in the drawing. There is a V-shaped line of juncture at 32, central and longitudinal of the curtain, and thus one of the curtain portions 5 projects a V-shaped end into the other curtain portion. In practice I prefer to have the relatively opaque portion 31 project a V-shaped end into the relatively transparent or translucent portion 30.
- 10 In order to make the dissolving device easily applicable to and removable from the lamp casings, I provide the frame casing 16 with a pair of hooks or other suitable members as shown at 35; and these members 35
- 15 hook into two of the ventilation openings 36 in the upper part of the upper lamp casing 10. In the bottom part of casing 16 I provide a transverse angle bar 37 which bears back against the lower edge of the lower casing 10. The casing 16 may thus be easily removed from the lamp casing by moving the lower end of casing 16 outwardly and then lifting it.
- When the curtain is wound upon the lower 25 roller 27, then the framed opening will be entirely curtained by the translucent portion 30 of the curtain; and the highest illumination will be obtained. (This is true for the arrangement shown herein; the opposite 30 is true if the dark end of the curtain be uppermost, and either arrangement may be used at will). This illumination, although it is very high and very efficient, is also most perfectly diffused; so that very little or no 35 shadow is cast. This diffusion is due to the translucency and diffusive quality of the material of the curtain. If it is now desired to gradually cut down the illumination, the curtain is wound upwardly (or it would be 40 downwardly if the curtain were reversed end for end); and as the curtain moves upwardly, the upper point 32^a of the opaque portion 31 moves up between the points of illumination. As the opaque 45 portion moves upwardly, the amount of illumination is gradually cut down, until, when the curtain opening is entirely covered by the opaque portion, the illumination is cut down to a minimum, or to none. During the dissolving action, as the opaque portion of the curtain is moved upwardly, it 50 will be noted that the point of the opaque portion moves first between the two lower points of illumination and then by its gradual spreading action gradually covers those 55 points of illumination; the point of the opaque portion then moving upwardly between the two upper points of illumination and then by the gradual spreading of the opaque portion, these two upper illuminations are covered. This action, which gradually 60 covers the points of illumination, rather than suddenly covering a single point of illumination, or suddenly and simultaneously 65 covering all of the several points of illumina-

nation at once, conduces substantially to the gradual dissolving of the light; cutting off gradually what little light there is which is direct rather than diffused and obviating any possibility of an apparent line of shadow 70 moving over the illuminated scene. However, it will be noted that almost all of the transmitted light is diffused by the translucent part of the curtain; so that the major action of dissolving the light is due to the perfectly gradual substitution of the relatively opaque part of the curtain for the relatively transparent or translucent part of the curtain. 75

I have now described a specific form of 80 my invention in some detail and particularity; but this description is given for the purpose of making my invention most easily intelligible rather than for the purpose of limiting the invention to the specific details 85 herein set forth. I believe my invention to be broad and fundamental rather than limited and specific; and the following claims are accordingly directed broadly as well as specifically to the device herein set forth 90 and described.

Having described a preferred form of my invention, I claim:

1. A light dissolve screen comprising a continuous curtain embodying a fabric one end part of which is translucent and light dispersive and the other end part of which is relatively opaque, the two parts joining each other on a V-shaped line. 95

2. A light dissolve screen comprising a continuous curtain embodying a thin fabric one end part of which is light in color and light dispersive and the other dark in color and the dark part extending a V-shaped portion into the light part. 100

3. In a device of the character described, an open front casing and a lamp therein, rollers at opposite edges of the front of the casing, and a continuous curtain on the rollers movable longitudinally therebetween, 105 said curtain having an end part which is translucent and light dispersive and an opposite end part relatively opaque and the opaque part projecting into and joining the translucent part on a V-shaped formation. 110

4. In a device of the character described, an open front casing and a lamp therein, a frame casing removably mounted on the lamp casing, rollers at top and bottom of said frame casing, and a curtain movable between the rollers, said curtain having a translucent end portion and a relatively opaque end portion, the two portions joining each other on a V-shaped line of juncture, said V being central and longitudinal of the 115 curtain. 120

5. In combination with a lamp having two spaced points of illumination, a dissolve curtain adapted to be moved before the lamp transversely to the line of spacing of the 125 130

points of illumination, said curtain having a relatively transparent portion and a relatively opaque portion, the two portions joining each other along a central and longitudinal V-shaped line.

6. In combination with a lamp having a plurality of sets each of two transversely spaced points of illumination, the sets being longitudinally spaced, a dissolve curtain 10 adapted to be moved before the lamp longitudinally, said curtain having a relatively transparent portion and a relatively opaque portion, the two portions joining each other along a central and longitudinal V-shaped 15 line.

7. A light dissolving screen embodying a continuous sheet of material one end part of which is translucent and adapted to diffuse light in passing through it and the 20 other end of which is relatively opaque, the

two end parts joining each other on a V-shaped line of juncture, the axis of the V being longitudinal of the screen.

8. A light dissolving screen embodying a continuous curtain one end part of which is 25 translucent and dispersive of light and the other end part relatively opaque, the two parts joining each other on a line diagonal across the curtain.

9. A light dissolving screen embodying a continuous curtain of a thin fabric one end part of which is translucent and dispersive of light and the other end part relatively opaque, the two parts joining each other on a line diagonal across the curtain. 30 35

In witness that I claim the foregoing I have hereunto subscribed my name this 11th day of June, 1918.

HOWARD M. EWING.
